UNITED STATES PATENT OFFICE.

PERCY Q. WILLIAMS, OF HUNTINGTON, WEST VIRGINIA.

LEER CONVEYER.

Original application filed June 3, 1922, Serial No. 565,732. Divided and this application filed May 2, 1923.
Serial No. 636,267.

My invention relates to apparatus used upon a foundation 12 by means of a ring 55 in connection with leer conveyers in the manufacture of glassware, this being a divisional application of my co-pending application Serial No. 565,732 filed June 3, 1922.

An object of my invention is to provide a device whereby bottles being conveyed into a leer may be precluded from distortion.

Another object is to provide a device that will impart an oscillatory movement to the bottles as they are being conveyed into a leer.

Another object is to provide a device whereby such bottles may be sufficiently cooled in transit to the leer as to permit them to be freely stacked in the leer.

These and other objects are attained by the means described herein and disclosed in the accompanying drawings in which:

20 Fig. 1 is a plan view of a leer conveyer having a device of my invention embodied therein.

Fig. 2 is a side elevation of Fig. 1.

25 Fig. 3 is a cross sectional view on line 3—3 of Fig. 1.

Fig. 4 is a cross sectional view on line 4—4 of Fig. 2.

In a device embodying my invention, articles such as glass bottles and the like are directed by means of a chute 5 to an endless conveyer belt 6 which carries the articles to a leer 7, where the articles are annealed. As the bottles are carried by the conveyer belt, they become somewhat cool, but are still sufficiently soft and pliable that, if allowed to lie motionless upon the belt, they will lose the form originally imparted to them. This is particularly true of bottles of the size and shape formerly known as beer bottles.

As the bottles are carried by the conveyer belt 6, they are rolled laterally between the sides of the way or channel 8, thru which they are carried, thereby precluding the still soft glass from settling and distorting the shape of the bottles.

This rolling and oscillating motion is accomplished by means of a series of air blasts which operate upon the bottles alternately and from opposite sides of the way.

The conveyer may comprise a frame 9, pivotally mounted upon a tubular support 10. A draft of air may be directed thru the support by means of a pipe 11, supported

upon a foundation 12 by means of a ring 13, having a flange 14 which is adapted to bear upon the support 10. The pipes 15 are mounted upon the pipe 11 in any suitable manner, as by means of a split ring 16, having radial flanges 17 which are bolted upon one another, see Fig. 4. The ring 16 has flanged slots 18 formed in it, the flanges 19 serving to position and retain the lower ends of the pipes 15. The pipes 15 communicate with air chambers 20, formed in the casings 21 which are mounted on the frame 9, and extend longitudinally thereof. The chambers 20 communicate with a number of blast nozzles 22 disposed above and adapted to divert the air blast transversely to the belt 6, intermediate the belt and the side bars 23 and 24. Communication between the blast nozzles and the chambers 20 is effected by the ports 25, and the valves 26 are adapted to control communication thru the ports 25. A number of blast nozzles 22 are disposed adjacently to one another thruout the length of the frame and on each side of the belt. A number of angular brackets 27, having elongated slots 28, are mounted upon the upper surface of frame 9 and support side bars 23 and 24 extending lengthwise of and above the belt 6. The brackets 27 may be adjusted so as to vary the width of the way 8 formed above the belt 6, such adjustment being made by means of bolts 29 mounted on the frames and extending thru the slots 28 in the brackets 27.

A nozzle 30 communicating with one of the pipes 15 is adapted to direct part of the air blast lengthwise of the way 8. By referring to Fig. 1, it is readily apparent that by closing certain of the ports 25 between their respective nozzles 22 and the chambers 20, it is possible to secure air drafts in opposite directions at spaced intervals throughout the length of the way 8. This structure is of vital importance when the conveyer carries bottles of the type known as beer bottles. These alternate air drafts serve to roll the bottles from side to side, thereby precluding caving in or distortion of such bottles.

The conveyer structure may be of the ordinary type such as used for this work, however, I prefer to use my invention with a conveyer such as is disclosed in my copending applications Serial Numbers 516,518 and

565,732 which may be described as comprising the endless conveyer belt 6 of asbestos composition or the like mounted to run continuously on the rolls 31 and 32. The frame 5 9 comprises an upper and a lower track, each track consisting of bars 33 mounted on brackets 34 which are in turn supported by angle irons 35 extending longitudinally of the frame, the angle irons being spaced by 10 bars 36. See Fig. 3. Rollers 37 are revolvably mounted on axles 38 and are adapted to ride upon the bars 33. The axles 38 also carry suitable brackets 39 to which rods 40 are secured, the belt 6 in turn being secured 15 to the rods 40 in any suitable manner such as by means of rivets. The links 41, 37 and 42 of the chain 43 which connects adjacent axles 38 is capable of separation at any of its joints to permit the removal of the belt and 20 roller structure. Suitable sprockets 44 and 45 revolvably mounted at the two ends of the frame and are adapted to carry the chains 43 to which the belt 6 is attached. Power may be transmitted to the sprockets 45 by any 25 suitable means such as a motor 46 and chain drive 47 whereby motion is imparted to the belt 6.

In operation of my device bottles pass to the belt 6 by way of the chute 5. The belt 30 being continuously in motion carries the bottles thru the way 8 wherein they are rolled from side to side by means of the air blasts from the nozzles 22, one or a group of such nozzles being open and discharging the air 35 blasts and a corresponding nozzle or group of nozzles on the opposite side of the way being closed. The oscillatory motion thus imparted to the bottles as they are carried along on the belt, precludes them from being distorted before being sufficiently cooled by the blasts of air and when sufficiently cooled they may be carried into the leer and stacked promiscuously. The number of defective bottles is thus materially reduced and 45 considerable saving in production cost is effected.

What I claim is:

1. In a device of the class described the combination of a conveyer for bottles to be 50 rolled on their sides, of a series of nozzles to direct blasts of air transversely of the conveyer, adjacent nozzles directing the air

blasts in opposite directions whereby the air blasts may cool and roll the bottles.

2. In a device of the class described the 55 combination of an endless conveyer and automatic means for supplying cooling air along the surface of the conveyer.

3. In a device of the class described the combination of a conveyer and means for 60 directing blasts of air transversely and longitudinally of the conveyer.

4. The combination with a leer, of an endless belt conveyer for carrying ware to the leer, said conveyer having a receiving end 65 remote from the leer and a discharging end adjacent the leer, means for delivering ware to said receiving end, and automatic means for supplying cooling air at a point adjacent the receiving end of the conveyer and directing 70 said air over the surface of the conveyer lengthwise thereof toward the discharge end.

5. The combination with a leer, of an endless belt conveyer for carrying ware to the leer, said conveyer having a receiving end 75 remote from the leer and a discharging end adjacent the leer, means for delivering ware to said receiving end, and automatic means for supplying cooling air at different points lengthwise of the conveyer and directing 80 said air against the ware on the conveyer.

6. The combination with a leer, of an endless belt conveyer for carrying ware to the leer, said conveyer having a receiving end remote from the leer and a discharging end 85 adjacent the leer, means for delivering ware to said receiving end, and a series of air nozzles along the conveyer arranged alternately on opposite sides of the conveyer for directing blasts of air across the conveyer. 90

7. The combination with a leer, of an endless belt conveyer for carrying ware to the leer, said conveyer having a receiving end remote from the leer and a discharging end adjacent the leer, means for delivering ware 95 to said receiving end, a series of air nozzles along the conveyer, and valves individual to said nozzles for controlling the supply of air therethrough.

In testimony whereof, I have hereunto 100 subscribed my name this 26th day of April, 1923.

PERCY Q. WILLIAMS.
